DESIGN FOR A VACUUM CLEANER CASING

Harley J. McAllister, Wheaton, Ill., assignor to Franklin McAllister Corporation, a corporation of Illinois

Application October 30, 1945, Serial No. 123,336
Term of patent 14 years

(Cl. D9—2)

To all whom it may concern:

Be it known that I, Harley J. McAllister, a citizen of the United States, residing at Wheaton, in the county of Du Page and State of Illinois, have invented a new, original, and ornamental Design for a Vacuum Cleaner Casing, of which the following is a specification, reference being had to the accompanying drawing, forming part thereof.

I claim:

The ornamental design for a vacuum cleaner casing, as shown.

HARLEY J. McALLISTER.
